UNITED STATES PATENT OFFICE.

CHARLES A. MANN, OF BUFFALO, ASSIGNOR OF ONE-HALF TO ADOLPH C. KNOTHE AND FRANK KNOTHE, OF NEW YORK, N. Y.

SNAP-HOOK.

SPECIFICATION forming part of Letters Patent No. 407,096, dated July 16, 1889.

Application filed January 10, 1889. Serial No. 295,917. (No model.)

To all whom it may concern:

Be it known that I, CHARLES A. MANN, a citizen of the United States, and a resident of Buffalo, in the county of Erie and State of New York, have invented new and useful Improvements in Suspender-Buckles, of which the following is a specification.

This invention relates to a suspender snap-hook, and has the object to produce a cheap hook of this class having few parts, and which shall have no projecting parts which are liable to chafe the clothing or disengage the hook from the suspender by catching the vest or other garment.

The invention consists of the improvements which will be hereinafter fully described, and pointed out in the claim.

In the accompanying drawings, Figure 1 is a perspective view of my improved snap-hook. Fig. 2 is a perspective view of the portion of the hook constituting the frame. Fig. 3 is a similar view of the tongue portion thereof. Fig. 4 is a cross-section, and Fig. 5 a longitudinal section, of the snap-hook.

Like letters of reference refer to like parts in the several figures.

A represents the back plate or frame, formed at one end with a hook b, which is designed for engagement with the ring of the suspender, and at its opposite end with a loop c, which is attached to the suspender-ends, as shown by dotted lines in Fig. 1.

D is a spring-tongue attached to the frame A and bearing at its outer end against the free end or nose of the hook b. The tongue D is formed at its inner portion with a return bend or leaf d, which rests against the adjacent front side of the frame A, the tongue, with its branch d, forming a tongue-frame which is approximately U-shaped. The tongue, with its branch d, is preferably constructed of a single piece of spring-brass. The inner portion of the tongue is confined between two ears e e, formed at the edges of the frame A, and is provided with laterally-projecting pins or pivots f, which fit in openings or perforations g, formed in the outer portions of the ears e. These openings are made somewhat larger than the pivots f, so as to give the lat-

ter a certain play in the openings. In depressing the tongue D its inner leaf d is also deflected and caused to move outwardly on the frame, thus resisting the inward movement of the tongue and relieving the pivots f of a part of the strain. The pivots f prevent the tongue D from moving lengthwise on the frame, and the ears e hold it against lateral displacement.

The portion of the tongue D in line with the ears e is corrugated or depressed below the outer portion of the ears, as shown at h, and the pivots f are formed on this depressed portion, so as to enable the openings in the ears to be formed at a distance from the outer edges of the latter and bring the outer ends of the ears flush with the face of the tongue to prevent the ears from wearing the clothing.

The contiguous end portions of the tongue D and hook b overlap each other, and these end portions are both provided with offsets, as clearly shown in the drawings, so as to form a flush joint and produce a smooth continuous surface on the inner as well as on the outer side of the tongue and hook. This construction leaves the snap-hook free from projections which are liable to catch on the vest or other garment and cause accidental depression of the tongue and disengagement of the hook b from the ring attached to the suspender.

My improved snap-hook can be produced at small cost and is very simple in construction, being composed of but two pieces, which are formed of sheet metal by stamping. The ears e are stamped flat in the same plane with the frame A, and are afterward bent at right angles to the frame, the openings in the ears being passed over the pins f of the tongue in the act of bending the same up, thus attaching the tongue, with its branch d, to the frame in a simple and inexpensive manner without any other fastening.

I claim as my invention—

In a snap-hook, the combination, with the frame A, provided at one end with a hook b and at its opposite end with a loop c, and having on its lateral edges upwardly-projecting lugs e, of a U-shaped spring-tongue D, hav-

ing its lower branch *d* resting upon the frame A, and provided on its upper branch with laterally-projecting pins *f*, depressed below the upper branch of said tongue and pivoted between the ears of the frame, whereby the tongue is held from both lateral and lengthwise movement on the frame, and an offset formed on the forward front end of the tongue

and engaging against the end of the hook *b*, substantially as set forth. 10

Witness my hand this 27th day December, 1888.

CHARLES A. MANN.
